UNITED STATES PATENT OFFICE

LEOPOLD LISSE, OF BERLIN-LICHTERFELDE, GERMANY

BLASTING METHOD AND TAMPING CARTRIDGE WITH UTILIZATION OF LIQUEFIED GASES

Application filed March 14, 1929, Serial No. 347,140, and in Germany October 22, 1928.

This invention relates to a blasting method and to the cartridge required for the same, specially with utilization of liquefied gases.

The novelty consists in the interposition of solid tamping over the entire length of the bore hole, said tamping at the deepest point of the bore hole having a dynamite-like effect, the tamping near the mouth of the bore hole possessing less strong dynamic effect.

The novelty consists in the special construction of the intermediate tamping cartridges, so that the evaporation products are absorbed by these intermediate tamping cartridges. Another object is, to prevent reducing of the temperature of the gases from explosion, so that the gas volume depending on the temperature is maintained constant.

According to the new method different effects can be obtained in one and the same bore-hole with the same kind of cartridge by the interposition of the solid intermediate tampings. For such cases two kinds of blasting cartridges had to be used hitherto, i. e. cartridges of different compositions.

The new method consists in that the effect of the blasting cartridges at the deepest point of the bore hole is differentiated or increased in comparison with the effect of the blasting cartridges in the upper portion of the bore hole by inserting between parts of the cartridge column a solid body (for instance salt-dust or similar tamping cartridges). If for example in a bore hole, three meters long at the inner end three or four cartridges, each 30 cms. long, i. e. a charging column of 0,90 to 1,20 meters is used, three tamping cartridges, for instance cartridges of salt dust, each 30 cms. long together 0,90 cms. long, are inserted and on these intermediate cartridges two or more blasting cartridges are placed, different effects of the two portions of the charging columns will be obtained at the ignition.

The blasting cartridges in the inner end of the bore hole are enclosed from both sides, i. e. by the wall of the inner end of the bore hole and by the salt-dust cartridges interposed between the two charges. The cubic charging density is consequently not reduced

as hitherto by the hollow space between the inner charge column and the charge column near the mouth of the bore hole. The explosive detonates therefore with less alterations in the explosion space formed by the length of the charge column. The efficiency of the cartridges in the inner end of the bore hole remains constant, whilst the efficiency of the cartridges near the mouth of the bore hole is reduced as these cartridges, which rest at the inner side on the intermediate tamping, have at the other side in the mouth of the bore hole an enlarged explosion space whereby the charge density is reduced. By the intentional enlarging of the explosion space a reduction of the efficiency is obtained, which is generally desirable at the mouth of the bore hole. With solid explosives the transmitting possibility is low and extends only over a few cms. According to the novel blasting method the transmitting capability is almost unlimited and extends over 2,4 meters as experiments have shown. It has been found that tamping cartridges of infusorial silica or mineral dust or salt fill the space sufficiently and prevent reducing of the charge density, that however, on the other hand, at the explosion salt-dust distributed in dust form generates extraordinarily great heat and causes consequently a reduction of the temperature and thereby of the volume of the gases.

These intermediate cartridges must therefore be made from materials which participate in the detonation. If the relation between the blasting cartridges, i. e. the quantity of the oxygen in excess, to the number of intermediate cartridges used is correct, at least 1×3 , the intermediate cartridges, filled with wood-dust from grinding, are completely combusted by the oxygen in excess. If it is desirable to improve this combustion, the catalizers commonly used in the explosive industry, for instance metals and salts, specially metal additions being much cheaper than aluminium, are preferably employed. 10 to 15% of such metal additions are added to the wood-dust from grinding, whereby the combustion is extraordinarily accelerated.

The envelopes of the intermediate cartridges are preferably made from porous and well permeable material, as filtering- and blotting paper, in order that the gases in the bore hole may be readily absorbed by the cartridges. These intermediate cartridges might have a hollow channel in which case the combustion will even be better at the moment of the detonation as the surface, on which the blasting gases act, is larger and the cartridge is more easily destroyed.

Two embodiments of the invention are illustrated, by way of example, in the accompanying drawing.

Fig. 1 shows a bore hole with three blasting cartridges *a* in the inner end, several intermediate tamping cartridges *b* on said blasting cartridges *a*, and two blasting cartridges *a* on the intermediate tamping cartridges *b*.

As shown in Fig. 2, the blasting cartridges *c* and the intermediate tamping cartridges *d* might alternate, the intermediate cartridges *d* having a central longitudinal channel *e*.

For the intermediate tamping cartridges any oxidizable substances, organic or inorganic, with or without addition of a neutral mass may be used.

I claim:—

1. A blasting method with utilization of liquefied gases consisting in charging the bore hole alternately with impregnated blasting cartridges and with tamping cartridges composed of oxidizable substances.

2. A blasting method with utilization of liquefied gases consisting in charging the bore hole alternately with impregnated blasting cartridges and with tamping cartridges composed of oxidizable substances and comburent salts.

3. A blasting method with utilization of liquefied gases consisting in charging the bore hole alternately with impregnated blasting cartridges and with tamping cartridges composed of oxidizable substances, comburent salts and neutral substances.

4. A blasting method with utilization of liquefied gases consisting in charging the bore hole alternately with impregnated blasting cartridges and with tamping cartridges containing wood dust, ammonium nitrate, and infusorial earth.

5. A blasting method with utilization of liquefied gases consisting in charging the bore hole alternately with impregnated blasting cartridges and with tamping cartridges containing oxidizable substances enclosed in permeable covers.

In testimony whereof, I affix my signature.
DR. LEOPOLD LISSE.
